United States Patent Office

Des. 190,752
Patented June 27, 1961

190,752

COCKTAIL SPOON OR THE LIKE

Anders Hostrup Pedersen, Copenhagen, Denmark, assignor to George Jensens Solvsmedie A/S, Copenhagen, Denmark

Filed Feb. 12, 1959, Ser. No. 54,574

Claims priority, application Denmark Aug. 28, 1958

Term of patent 14 years

(Cl. D44—29)

FIG. 1 is a front elevational view of a cocktail spoon showing my new design; and

FIG. 2 is a side elevational view thereof.

I claim:

The ornamental design for a cocktail spoon, as shown.

References Cited in the file of this patent

UNITED STATES PATENTS

D. 118,831	Norris	-----	Feb. 6, 1940
1,858,435	Conlon	-----	May 17, 1932

FOREIGN PATENTS

18,630	France	-----	May 27, 1914